UNITED STATES PATENT OFFICE.

JOHN LESLIE LOMAX, OF COLORADO SPRINGS, COLORADO, ASSIGNOR OF ONE-HALF TO HERMANN LOUIS OSWALD AND CRAFTON PATTON, BOTH OF COLORADO SPRINGS, COLORADO.

ACTUATING DEVICE FOR WIRE-PUSH-RELEASE CAMERAS.

Application filed September 7, 1926. Serial No. 183,961.

My invention relates to actuating devices for wire push release cameras. My object in general is to provide a device which can be tripped by a wild animal, bird or reptile and when tripped will actuate the push wire of a camera to operate the shutter. Specific objects are to provide means for setting the device, for releasing the setting means, for holding flash light power, for igniting the flash light powder, and for holding the push wire cable of a camera in the proper position to be acted upon by the actuating members of the device. Other objects will appear as the description progresses.

Figure 1 represents a plan view of the device; Fig. 2, a side elevation of Fig. 1; and Fig. 3, an enlarged fragmentary cross sectional elevation of the device.

Although I show the preferred embodiment of my invention, I do not thereby limit myself to the precise details of construction shown, but wish it understood that within the scope of what hereinafter is claimed, various modifications and changes in the construction may be made without departing from the spirit of the invention.

A sheet metal clip 1 is mounted on the front portion of a cylinder 2 and supports a platform A. A box 3 is mounted on the platform A and is provided with a lug 4 to which a trigger 5 is pivoted. A lid 6 is connected to the box 3 by the hinge 7 and is provided with a latch 9 engaging the trigger 5 at the front, and with an arm B at the rear.

A shaft 10 is mounted in vertical lugs 11 and 12 on the platform A and carries a trigger 13 and an arm 14. A spring 15 is wound about the shaft 10 and connected to the arm 14 to hold it back. A latch 16 provided with a trigger arm C is pivoted on the lug 12 and is held in normal position by an open spring 17. A wheel 18, having a serrated periphery, is rigidly mounted on the shaft 10 in alignment with a conduit D communicating with the box 3. A thimble 19 is secured to the underside of the platform A and contains a plunger 20 normally held in engagement with the serrated periphery of the wheel 18 by an open spring 21, the spring being held in position by a cap 22.

A main piston rod 24 carries a piston 25 and an open spring 26 within the cylinder 2 and extends through the rear end of said

cylinder. A clip 27 is mounted on the rear end of the main piston rod 24 and a longitudinally disposed latch bar 28 is pivoted to the clip 27. A clip 29 is mounted on the rear portion of the cylinder 2 and is provided with vertically disposed extensions 30 to which a longitudinally disposed trigger 31 is pivoted by a pivot 32.

A secondary piston rod 33 is disposed in the forward portion of the cylinder 2 and extends through the front end. A piston 34 and an open cushion spring 35 is mounted on the piston rod 33 within the cylinder 2 and an L-shaped guide plate 36 is mounted on the front end of said secondary piston rod. A clip 37 is mounted on the front end of the cylinder 2 and is adapted to hold the end of the camera cable 38 containing the push wire 39.

The main piston rod 24 is pulled back until the latch 28 engages the pivot 32 and presses down the short arm of the trigger 31. A string or wire 40 is attached to a bait 41. Flash light powder is deposited in the box 3 and the lid 6 is closed so that the latch 9 engages the trigger 5. The lever arm 14 is swung forward until the trigger arm 13 engages the latch 16. The device and camera are now left alone as long as desired or until an animal, bird or reptile disturbs the bait 41. When the bait is disturbed the pull on the string 40 causes the trigger 31 to push the latch 28 upward which releases the latch 28 so that the spring 26 drives the piston 25 forward. The compression of the air ahead of the piston 25 forces the piston 34 forward and moves the plate 36 against the wire 39 and opens the camera shutter. As the plate 36 moves the wire 39 it also strikes the trigger 5 and releases the latch 9 which permits the lid 6 to fly open due to the spring hinge 7. As the lid 6 flies open the arm B strikes the trigger 13 and releases the latch 16 and permits the spring 15 to revolve the shaft 10 rearward. This causes the serrated periphery of the wheel 18 to rub against the plunger 20 and produce sparks which ignite the flash light powder in the conduit D and box 3. The spring 35 pushes the piston 34 back as the air behind it leaks out and permits the wire 39 to return to normal position thereby permitting the camera shutter to close.

The box 3 may be made to telescope so

that in the event that a larger quantity of powder is desired than the box normally holds, the side telescoping members T may be provided to be pulled out to increase the capacity of the box.

The plunger 20 is made of the usual material used in lighting devices of this character such as gas lighters.

Having thus described my invention, what I claim as new and desire to secure by Letters Patent is:

1. In a device of the class described, the combination of a horizontally disposed cylinder; a box mounted on the front portion of said cylinder and provided with a lid carrying a front latch; a vertically disposed trigger mounted on the front of said box and cooperating with said front latch; and trigger means, adapted to cooperate with said lid, mounted at the rear of said lid; and a transversely disposed shaft mounted at the rear of said trigger means and carrying a lever and a latch cooperating with said trigger means.
2. In a device of the class described, the combination of a horizontally disposed cylinder; a box mounted on the front portion of said cylinder and provided with a hinged lid carrying a front latch; a vertically disposed trigger mounted on the front of said box and cooperating with said front latch; a trigger means cooperating with said lid and mounted at the rear thereof; a transversely disposed shaft mounted at the rear of said trigger means and carrying a lever and a latch cooperating with said trigger means; a serrated wheel mounted on said shaft; cooperating means with said wheel to ignite flash light powder within said box, and communicating means between said box and said igniting means.
3. In a device of the class described, the combination of a horizontally disposed cylinder; a main piston rod within and extending through the rear end of said cylinder; a piston on said piston rod within said cylinder; an actuating spring on said piston rod; a horizontally disposed latch mounted on said piston rod; and a horizontally disposed trigger mounted on said cylinder and adapted to release said horizontally disposed latch; for the purposes set forth.
4. In a device of the class described, the combination of a horizontally disposed cyl-

inder; a main piston rod within and extending through the rear of said cylinder; a piston on said piston rod within said cylinder; an actuating spring on said piston rod; a horizontally disposed latch mounted on said piston rod; a trigger mounted on said cylinder and adapted to release said latch; and a secondary piston rod within and extending through the front of said cylinder; a plate mounted on the front and a piston mounted on the rear of said secondary piston rod; for the purposes set forth.

5. In a device of the class described, the combination of a horizontally disposed cylinder; a main piston rod within and extending through the rear of said cylinder; a piston on the front end of said main piston rod; a horizontally disposed latch mounted on said main piston rod; a trigger mounted on said cylinder and adapted to release said latch; an actuating spring on said main piston rod; a secondary piston rod within and extending through the front of said cylinder; a plate mounted on the front and a piston mounted on the rear of said secondary piston rod; a cushion spring on said secondary piston rod, and a camera cable release holder mounted on the front of said cylinder.

6. In a device of the class described, the combination of a horizontally disposed cylinder; a main piston rod, carrying a piston, mounted within said cylinder and extending through the rear end; an actuating spring on said piston rod; a horizontally disposed latch mounted on said piston rod; a horizontally disposed trigger for said latch mounted on said cylinder; a secondary piston rod extending through the front end of said cylinder; a plate mounted on the front end of said secondary piston rod; a piston mounted on said secondary piston rod within said cylinder; a box for flash light powder mounted on the front portion of said cylinder and provided with a hinged lid carrying a latch on the front; a trigger mounted on said box to cooperate with said latch on said lid; a trigger means adapted to be operated by said lid, mounted at the rear thereof; a transversely disposed shaft mounted at the rear of said trigger means and carrying a lever and a latch to cooperate with said trigger means; and an igniting means adapted to be operated by said shaft.

JOHN LESLIE LOMAX.
